UNITED STATES PATENT OFFICE.

CONYERS BUTTON, OF PHILADELPHIA, PENNSYLVANIA.

DESIGN FOR STOCKING-FABRIC.

Specification forming part of Design No. 5,101, dated July 11, 1871.

To all whom it may concern:

Be it known that I, CONYERS BUTTON, of Philadelphia, county of Philadelphia, State of Pennsylvania, have invented or produced a Design for a Stocking-Fabric, of which the following is a specification:

In the accompanying drawings the figure represents my design for a stocking fabric, the principal features of which are the stripes A and the bars B.

Each stripe A is composed of a group of ribs, as shown, and the bars B, which are arranged in couples between the stripes A, are each orna-

mented by a double row of spots, in the manner clearly represented in the drawings.

Irrespective of the colors employed, I claim—

The design for a stocking-fabric, substantially as described, and as represented in and by the accompanying drawings.

In testimony whereof I have signed my name to this specification in the presence of two subscribing witnesses.

CONYERS BUTTON.

Witnesses:

WM. A. STEEL,
HARRY SMITH.
